UNITED STATES PATENT OFFICE.

WALTER C. JACKSON, OF DENVER, COLORADO.

IRONING-BOARD FASTENER.

1,387,073.

Specification of Letters Patent. Patented Apr. 13, 1920.

Application filed September 11, 1919. Serial No. 323,098.

To all whom it may concern:

Be it known that I, WALTER C. JACKSON, a citizen of the United States, residing at Denver, in the county of Denver and State of Colorado, have invented a new and useful Ironing-Board Fastener, of which the following is a specification.

This invention relates to fastening devices, and more particularly to devices of this character especially constructed for use in securing ironing board covers, to the ironing board supporting the same.

The primary object of the present invention is to provide a securing element including resilient wire members, which will grasp or penetrate portions of the cover to firmly secure the same to the ironing board, and at the same time afford a securing device which may be readily and easily detached, in the event that it becomes necessary to change or remove the same.

A further object of the invention is to provide a device of this character which will be adjustable to enable the same to be secured to ironing board covers, employed in connection with ironing boards of various widths and sizes.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a bottom plan view of an ironing board having the securing means constructed in accordance with the present invention, as applied thereto, and

Fig. 2 is a perspective view of the securing device.

Referring to the drawing in detail, the invention is shown as applied to the cover 5, positioned on the usual ironing board 6, the edges of the cover extending around the edges of the board 6, and engaging the rear surface of the ironing board as indicated by Fig. 1 of the drawing.

The device forming the subject of the present invention includes the opposed sections 7 and 8, each of which includes a length of resilient wire material, bent to form a loop 9, intermediate the length thereof, the ends of said loop 9, or leg portions 10

and 11 thereof having their extreme ends curved as at 12, to provide the eyes 13, whereby one section may be interlocked with the other.

The leg portions 14, of the length of wire, are continuations of the leg portions 10 and 11 of the loop, the same extending at angles with relation to the eyes 13 and cross each other at points between the leg portions 10 and 11 of the loop 9, the extreme ends of the said leg portions 14 being sharpened as at 15, to provide spurs to enable the fastener to be secured to the ironing board cover by piercing the same.

These spurs are relatively short, and extend in a direction toward the eyes 13, or toward the point of connection between the sections forming the fastener, whereupon the device, in order to be removed from the cover, must be moved against the resiliency of the leg portions 10 and 11 of the loops 9, the leg portions 10 and 11, as shown, normally hold the spurs to their positions within the cover.

From the foregoing it will be seen that the leg portions of the sections may be moved to various angles, with relation to each other, thereby allowing the fastener to be secured to ironing board covers wherein the edges of the ironing board cover which overlap the sides of the ironing board, are a greater or less distance apart.

Having thus described the invention, what is claimed is:

A clasp including in combination a pair of opposed sections, each of said sections being identical in construction and comprising a length of flexible material bent to provide a loop portion and a pair of opposed leg members, the loop portion overlying the leg members of the section of which the loop portion forms a part, each of said leg members having an eye formed at one end thereof, the eyes of the leg members of one section adapted to receive the opposite section, said leg members crossing each other at a point directly under the loop portion, and spurs formed at the ends of the leg members.

In testimony that I claim the foregoing as my own I have hereto affixed my signature in the presence of two witnesses.

WALTER C. JACKSON.

Witnesses:

CHAS. EDGAR PRATHER,
EVERETT C. MESSING.
